UNITED STATES PATENT OFFICE.

WILLIAM B. PAINTER AND ELIZABETH A. REEVES, OF RIVER ROUGE, MICHIGAN.

ATTACHMENT FOR OVENS.

Application filed March 6, 1922. Serial No. 541,292.

To all whom it may concern:

Be it known that we, WILLIAM B. PAINTER and ELIZABETH A. REEVES, citizens of the United States of America, residing at River 5 Rouge, in the county of Wayne and State of Michigan, have invented certain new and useful Improvements in Attachments for Ovens, of which the following is a specification, reference being had therein to the accompanying drawings.

This invention relates to ovens and particularly to trays which are movable within the same.

In the present state of the art various devices have been found which are provided with a plurality of removable vertically spaced trays or shelves. However, whenever it is desired to move a tray vertically with respect to a burner beneath the bottom 20 of the oven it sometimes becomes necessary to open the oven door and to keep the same open during the entire operation of changing or adjusting the trays. This method lowers materially the temperature within 25 the oven. Moreover, after the oven has been heated for a considerable length of time the trays become hot and it is necessary to use gripping means to remove and replace the trays.

It is the object of the present invention to overcome all of the objectionable features referred to above and to provide a simple mechanical construction which may be advantageously used in any type of oven.

To this end the invention consists in the construction as hereinafter set forth.

In the drawing:

Fig. 1 is a top plan view of an oven with parts broken away.

Fig. 2 is a longitudinal sectional view taken on the line 2-2 of Figure 1.

Fig. 3 is a transverse sectional view taken on line 3-3 of Figure 2.

Fig. 4 is an end view with parts broken away.

Fig. 5 is an end elevation of a modified construction.

Referring now to the drawing in which like characters of reference designate corresponding parts throughout the several views, the numeral 1 designates an oven casing provided with the usual lining 2 and intermediate packing 3.

A plurality of spaced vertical guide members 4 are secured to opposite end walls of the lining 2 and are adapted to engage

spaced slots 5 formed in the ends of a movable tray 6. A pair of flexible members 7 are terminally secured to the tray adjacent to the slots 5 and are secured intermediate their ends to the lower ends of a pair of flexible members 8 and 9 respectively, which are trained over a pair of aligned pulleys 10 secured to the upper wall of the lining adjacent to the opposite ends thereof. The flexible member 9 is also trained over a pulley 11 which is secured to the upper wall of the lining intermediate the aligned pulleys 10 and is offset with respect thereto. A flexible member 12 is secured to the free ends of the flexible members 8 and 9 and extends through aligned openings 13 and 13' formed respectively in the oven casing and lining. A hollow handle member 14 is secured to the free end of the flexible member.

Various means may be employed for retaining the trays in adjusted position and in the preferred embodiment of the invention a relatively narrow notch 15 is formed in the oven casing in communication with the opening 13 and is adapted to receive and frictionally hold a portion of the flexible member 12.

In the modified form of the invention, a plurality of vertically spaced pegs or studs 16 are secured by any suitable means to the oven casing beneath the opening 13. These pegs are adapted to extend through the handle member 14 to retain the trays in any desired position of adjustment.

With the construction described the trays may be easily and quickly moved to any position of vertical adjustment within the oven without opening the oven door.

While it is believed that from the foregoing description the nature and advantages of the invention will be readily apparent, we desire to have it understood that we do not limit ourselves to what is herein shown and described, and that such changes may be resorted to when desired as fall within the scope of what is claimed.

What we claim as our invention is:

1. The combination with an oven, of guide members secured directly to the walls of said oven, a movable tray located in said oven and having slots formed therein engaging said guide members, flexible members secured to said tray, pulleys secured to one wall of said oven, flexible members secured to the flexible members aforesaid and trained over said pulleys, a pulley secured to one

wall of said oven and supporting one of the last mentioned flexible members, and a flexible member secured to both of the last mentioned flexible members and extending 5 through said oven.

2. The combination with an oven, of guide members secured to said oven, a movable tray located in said oven having slots formed therein engaging said guide members, flexible members terminally secured to said tray, a pair of pulleys secured to said oven, flexible members secured to the flexible members aforesaid and trained over said pulleys, a pulley secured to said oven and supporting 10 one of the last mentioned flexible members, and a flexible member secured to both of the last mentioned flexible members and extending through said oven, said oven having a notch formed therein adapted to receive and 15 frictionally hold a portion of the last mentioned flexible member.

3. The combination with an oven, of a movable tray located in said oven, flexible members secured to said tray, a pair of pulleys secured to said oven, flexible members secured to the flexible members aforesaid and trained over said pulleys, a pulley secured to said oven and supporting one of the last mentioned flexible members, said oven having an opening formed therein, and a flexible member secured to both of the last mentioned flexible members and extending through the opening in said oven, said oven also having a notch formed therein in communication with said opening adapted to receive and frictionally hold a portion of the last mentioned flexible member.

4. The combination with an oven, of a movable tray located therein, guide means for said tray, flexible members terminally secured to said tray at the opposite ends thereof, a pair of aligned pulleys secured

to the upper wall of said oven, flexible members secured to the flexible members aforesaid intermediate the ends thereof and 45 trained over said pulleys, a pulley secured to the upper wall of said oven intermediate the aligned pulleys and offset with respect thereto, the last mentioned pulley supporting one of the last mentioned flexible members, and 50 a flexible member secured to the free ends of both of the last mentioned flexible members and extending through said oven, said oven having a notch formed therein adapted to receive and frictionally hold a portion of 55 the last mentioned flexible member.

5. The combination with an oven, of a movable tray located in said oven, flexible members secured to said tray, pulleys secured to one wall of said oven, flexible members secured to the flexible members aforesaid and trained over said pulleys, a pulley secured to one wall of said oven and supporting one of the last mentioned flexible members, and means secured to both of the 65 last mentioned flexible members for actuating said tray.

6. The combination with an oven, of a movable tray located in said oven, flexible members secured to said tray, pulleys secured to one wall of said oven, flexible members secured to the flexible members aforesaid and trained over said pulleys, a pulley secured to one wall of said oven and supporting one of the last mentioned flexible 70 members, a flexible member secured to both of the last mentioned flexible members, and means engageable with the last mentioned flexible member for retaining said tray in any position of adjustment.

In testimony whereof we affix our signatures.

WILLIAM B. PAINTER.
ELIZABETH A. REEVES.
